DESIGN FOR A PERFUME CONTAINER

John Rubel, New York, N. Y.

Application December 18, 1944, Serial No. 116,956

Term of patent 7 years

(Cl. D58—6)

To all whom it may concern:

Be it known that I, John Rubel, a citizen of the Republic of France who has declared his intentions of becoming a citizen of the United States, residing in New York city, in the county of New York and State of New York, have invented a new, original, and ornamental Design for a Perfume Container, of which the following is a specification, reference being had to the accompanying drawing, forming part thereof.

Fig. 1 is a side perspective view of a perfume container, showing my design,

Fig. 2 is a front elevational view of the perfume container shown in Fig. 1.

Fig. 3 is a side elevational view of the perfume container shown in Fig. 1, with its dipper member in raised position, and

Fig. 4 is a side elevational view of the dipper member thereof.

I claim:

The ornamental design for a perfume container, substantially as shown.

JOHN RUBEL.
